CLAIM

What is claimed is the ornamental design for a shoe insole, as shown and described.

DESCRIPTION

FIG. 1 is a front, top, and right side perspective view of a shoe insole showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another front elevation view of the shoe insole in condition of use.

The broken lines used in the drawings are for the purpose of illustrating environmental structure and form no part of the claimed design. The dash dot dash broken lines shown in the drawings illustrate the boundary of the claim and form no part thereof.
